UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

EMERGENCY DEVICE.

SPECIFICATION forming part of Letters Patent No. 783,507, dated February 28, 1905.

Application filed June 16, 1904. Serial No. 212,778.

To all whom it may concern:

Be it known that I, FRED B. COREY, a citizen of the United States, residing at Schenectady, county of Schenectady, State of New York, have invented certain new and useful Improvements in Emergency Devices, of which the following is a specification.

My invention relates to improvements in means for automatically controlling motors and power-actuated brakes in case of an emergency, and is intended for use especially in connection with electrically-propelled vehicles or trains employing a braking system actuated by compressed air. In order to insure against accidents in high-speed work, it is essential that provision should be made for cutting off the power and applying the brakes in case the motorman becomes incapacitated by sickness, accident, or death. To accomplish this result, it has been proposed heretofore to provide a valve operative upon the release of the controller-handle to apply the brakes, together with a switch similarly operative for cutting off the power from the motors. The apparatus which has been used heretofore to accomplish this result consists of a spring-pressed button mounted on the controller-handle, which the motorman must keep depressed during the operation of the vehicle in order to prevent application of the brakes and cutting off the power. Such an arrangement is illustrated and described in Patent No. 755,750, issued to me March 29, 1904. An objection to this arrangement arises from the fact that the muscles of the motorman's hand which is used in operating the controller must be kept under strain during the entire operation of the vehicle in order to keep the button depressed. This strain is very fatiguing, and objection has been made on this ground to the arrangement described above.

The object of my present invention is to provide means for relieving the strain upon the motorman's hand by reducing the pressure which is required upon the button and by allowing the button a certain amount of play without resulting in the operation of the emergency device. I accomplish this by provid-

ing a latch which engages the operating mechanism when the button has once been depressed and which consequently relieves the button of a portion of the pressure required for holding the emergency device in inoperative position and at the same time admits of a certain range of movement of the button. The button is arranged, however, to engage the latch and to trip it if the button is wholly released by the motorman. In this manner the safeguards offered by the former arrangement are maintained, while the objection thereto is eliminated.

My invention will best be understood by reference to the accompanying drawings, in which—

Figure 1 shows a side elevation, partly in cross-section, of a controller arranged in accordance with my invention. Fig. 2 is a plan view showing a detail of the connection between the brake-applying valve and the controller-handle; and Fig. 3 is a detail of the controller-handle, showing the latch in operative position.

In the drawings, 1 represents the operating-shaft for a controller, to which is secured the controller-handle 2. On the shaft 1 is loosely journaled the sleeve 3, which is provided with a flange 4 and a spiral spring 5. The spring 5 tends to rotate the sleeve 3 so as to bring a lug on flange 4 into engagement with a stationary stop 6, as shown in Fig. 2.

7 is a button carried by the controller-handle and normally pressed upward in the position shown by the compression-spring 8. The lower end of the spindle on which button 7 is mounted engages the long arm of a pivoted lever 9, the short arm of which is engaged by a compression-spring 10, which adds its pressure to that of spring 8 in maintaining button 7 in its raised position. The short arm of lever 9 engages the notched end of the pivoted lever 11, the other notched end of which engages a vertically-movable member 12. When button 7 is depressed, rocking levers 9 and 11, the member 12 is pressed down so that its lower end is brought into engagement with the notch 13 in flange 4. By

this means the sleeve 3 may be locked to the controller-shaft 1 and rotated therewith away from the stationary stop 6.

The flange 4 carries a second lug 14, (shown 5 in Fig. 2,) which when the flange is in the position shown in this figure engages one end of a pivoted lever 15, the other end of which engages the spindle 16, which operates a valve 17. The valve 17 is properly arranged for 10 establishing the connections for applying the brakes. It will be understood that in a straight air-brake system these connections would be such as to raise the pressure in the train-pipe for applying the brakes and in an automatic 15 air-brake would be such as to lower the pressure in the pipe for applying the brakes. Such connections are shown in Patent No. 755,750, above referred to, and in other patents and 20 applications. Hence it is not deemed necessary to illustrate the connections here, since the specific connections employed form no part of the present invention and are disclosed in prior patents. For the purpose of 25 the present invention it is sufficient to understand that when pivoted lever 15 is in the position shown, pressing against spindle 16, the valve 17 establishes the connections for applying the brakes. When flange 4 is locked to shaft 1 and is rotated therewith in the manner 30 previously explained, lug 14 will be moved away from lever 15 and valve 17 allowed to move to break the brake-applying connection.

The arrangement thus far described is shown in Patent No. 755,750, above referred to, and 35 has been described here merely for the purpose of enabling a clear understanding of the invention to be obtained.

Referring now to Fig. 3, 18 represents a pivoted latch which is pressed forward by the 40 leaf-spring 19. When the long arm of lever 9 is depressed, as shown in Fig. 3, latch 18 is consequently brought into engagement with this lever. The button 7 may then be raised out of engagement with the lever 9 without 45 producing an application of the brakes, the strain produced by spring 10 in Fig. 1 being taken up by the latch 18. The button 7 consequently has a certain range of movement and is pressed upward only by the spring 8, 50 which may be made merely strong enough to raise button 7 to its highest position if wholly released. If all pressure is removed from button 7, it will be raised to its highest position, 55 engaging the toe of latch 18 and releasing it from engagement with the lever 9, thereby permitting an application of the brakes. The same safeguard against accident is thus maintained in this as in the former arrangement, while the strain upon the motorman's hand is 60 diminished both by the range of movement allowed by the button and by the fact that the greater portion of the spring tension necessary for operating the mechanism may be taken up by the latch.

55 Although I have shown my invention as ap-

plied to a specific form of mechanism controlled by a button on the controller-handle, it will be understood that it is applicable to any other form of mechanism operative upon the release of any handle or lever which is normally under the control of the motorman during the operation of the vehicle, and although I have illustrated and described an emergency device consisting of a valve for applying the brakes my invention is applicable to the control of 75 other forms of emergency devices. Consequently I do not desire to limit myself to the particular construction and arrangement of parts shown; but I aim in the appended claims to cover all modifications which are within the 80 scope of my invention.

What I claim as new, and desire to secure by Letters Patent of the United States, is—

1. In a vehicle, in combination with an air-brake system, an operating-lever, means operative upon a release of said lever for applying the brakes, and means for preventing the 85 operation of said brake-applying means upon a partial release of said lever.

2. In a vehicle, in combination with an air-brake system, an operating-lever, a valve adapted and arranged to establish connections for applying the brakes, operative connections between said lever and said valve, and a latch 90 for said operative connections.

3. In a vehicle, in combination with an air-brake system, an operating-lever, a valve adapted and arranged to establish connections for applying the brakes, operative connections between said lever and said valve, a latch for 100 said operative connections, and means for releasing said latch when said lever is released by the operator.

4. In a vehicle, in combination with an air-brake system, a valve adapted and arranged to 105 establish connections for applying the brakes, an operating-handle, a spring-pressed member associated with said handle and adapted to be grasped by the operator, connecting means between said member and said valve, a latch 110 for said connecting means, and means for releasing said latch when the said member is released by the operator.

5. In a vehicle, in combination with an air-brake system, a valve adapted and arranged to 115 establish connections for applying the brakes, an operating-handle, a spring-pressed member associated with said handle and adapted to be grasped by the operator, connecting means between said member and said valve, a latch 120 arranged to engage said connecting means when said member is pressed by the operator, and means for tripping said latch when said member is released by the operator.

6. In a vehicle, in combination with an air-brake system, a valve adapted and arranged to establish connections for applying the brakes, spring-pressed controlling means for said valve, an operating-lever, means associated 125 with said lever for moving said controlling 130

means to strain the spring, a latch arranged to engage said controlling means when the spring is strained, and means for tripping said latch when said lever is released by the 5 operator.

7. In a vehicle, in combination with an air-brake system, a valve adapted and arranged to establish connections for applying the brakes, controlling means for said valve, a latch for 10 said controlling means, an operating-lever, and means for tripping said latch when said lever is released by the operator.

8. In a vehicle, in combination with an air-brake system, a valve adapted and arranged to 15 establish connections for applying the brakes, a spring-actuated lever controlling said valve, an operating-lever, means associated with said operating-lever for moving the first lever to strain said spring, a latch for said first lever, 20 and means for tripping said latch when said operating-lever is released by the operator.

9. In a controller, a spring-pressed lever, a 25 manually-controlled member adapted to move said lever to strain said spring, and a latch for said lever, said member being arranged to trip said latch when released by the operator.

10. In a controller, an operating-handle, a 30 spring-pressed lever, means associated with said handle adapted to be grasped by the operator and to move said lever to strain the spring, and a latch arranged to engage said lever when the spring is strained, said means being arranged to trip said latch when released by the operator.

35 11. In a vehicle, in combination with an air-brake system, a valve adapted and arranged to establish connections for applying the brakes, a spring-pressed device for moving said valve to apply the brakes, means for moving said 40 device against the pressure of the spring to prevent the application of the brakes, and means for taking up a portion of said spring-pressure when said device is moved so as to reduce the pressure on said moving means.

12. In a vehicle, an emergency device, a 45 spring tending to move said device to emergency position, means for straining said spring to render said device inoperative, and means for taking up a portion of the strain of the spring so as to reduce the strain on said strain- 50 ing means.

13. In a vehicle, a controlling-lever, an emergency device operative upon a release of said lever, and means for preventing the operation of said device upon a partial release of said 55 lever.

14. In a vehicle, a controlling-lever, an emergency device, operative connections between said lever and said device, a latch for said device, and means for tripping said latch when 60 said lever is released by the operator.

15. In a vehicle, an emergency device, a 65 spring tending to move said device to emergency position, a controlling-lever, means associated with said lever for straining said spring to render said device inoperative, a latch for the spring when strained, and means for tripping said latch when said lever is released by the operator.

16. In a controller, a spring-pressed lever, 70 means for moving said lever to strain the spring, and means for taking up a portion of the strain of the spring so as to reduce the strain on the straining means.

17. In a controller, an emergency device, a 75 spring tending to move said device to emergency position, means for straining said spring to render said device inoperative, and means for taking up a portion of the strain of said spring so as to reduce the strain on said strain- 80 ing means.

In witness whereof I have hereunto set my hand this 14th day of June, 1904.

FRED B. COREY.
